UNITED STATES PATENT OFFICE.

HENRY THOMAS PYE, OF MONTREAL, QUEBEC, CANADA.

GAME.

Application filed September 14, 1921. Serial No. 500,568.

To all whom it may concern:

Be it known that I, HENRY THOMAS PYE, residing at the city of Montreal, in the Province of Quebec, in the Dominion of Canada, have invented a new and useful Game, of which the following is the specification.

The invention relates to a game as described in the present specification and illustrated in the accompanying drawings that form part of the same.

The invention consists essentially of the novel features of construction pointed out broadly and specifically in the claim for novelty following a description in detail of the preferred form of the device.

The objects of the invention are to afford amusement for the young people and their elders and at the same time provide a skillful game which will exercise good judgment in determining angles and distances and generally to promote efficiency as well as providing a cheap and pleasurable indoor game.

In the drawings Figure 1 is a perspective view of the game complete.

Figure 2 is a longitudinal sectional view of the case showing the game board removed.

Figure 3 is a cross sectional view of the case and game board.

Figure 4 is a perspective detail of the glancing block.

Figure 5 is a longitudinal sectional view of the spring cue.

Like numerals of reference indicate corresponding parts in the various figures.

Referring to the drawings, the game board 1 is contained in the case 2, the former having the corner slots 3 and intermediate slots 4 midway of the length of the sides of the board, the several slots representing the pockets of a billiard table and situated in the same position in relation to the board.

The case 2 is formed with the bottom 5 secured to the sides 6 and ends 7 and 8, the end 8 having a central lower egress opening 9 below the cue opening 10, said cue opening being on a level with the game board 1, which is secured to the sides and ends intermediate of their height forming a retaining wall completely surrounding the board 1, except at the cue opening.

Beneath the game board 1 and above the bottom 5, the tray 11 slopes to the egress

opening 9, the walls 12 and 13 converging to said opening so as to direct the ball from the far end and intermediate pockets to the outlet 9, the chutes 14 directing the ball from the inner end pockets to the same opening 9.

The glancing block 15 is made with the flat straight front surface 16 and the curved back 17, and this block is held by the pivot 18 centrally between the sides 6 and towards the end 7, so that it is directly in alignment with the cue opening 10.

The cue 19 is formed with the head 20 and handle 21, the latter being of suitable corrugated material, preferably fibre.

The handle 21 is joined to the head 20 by the rod 22 which extends through the tube 23 closed in at the handle end by the screw cap 24, said screw cap having a central hole 75 for said rod.

The spiral spring 25 encircles the rod 22 between the head 20 and screw cap 24 within the tube 23, therefore by pulling on the handle 21 the head 20 compresses the spring 80 25, so that when the handle is released, the said head quickly returns to its original position and thus sends the ball 26 in the direction desired by the player similar to any spring gun.

The tube 23 is held in the holder 27, which is preferably in the shape of a small cylindrical block of wood upon which the thumb is placed in holding the cue in position for shooting.

In playing the game, the ball is placed on the spot in front of the cue 19 and the latter is guided by the hand into the position to shoot. The shot is made against the glancing block 15 either off the flat face or off the curved back according to the position that the block may be placed in. The block is not movable on the board, but it is situated as described centrally between the sides towards the opposite end from the spot on which the ball rests.

The player must call his shot and move the pivoted block around on its pivot to agree with the shot he calls, and if he is shooting for the corner pocket, the glance block is adjusted for that particular shot and he must hit the block in such a way with the ball as to carom it into the pocket.

There are many different shots that may be made on the curved face of the block and on the flat side, and to play the game scientifically each of said shots should be called.

Of course it is necessary to count, therefore each shot shall have a count, and the score kept much the same as in billiards.

What I claim is:

- 5 In a game, a board having box sides and a playing slot and ball return opening at one end, an inclined bottom secured in said slides having converging guides and inclined surfaces leading to said opening, a playing board flush with the bottom of said slot and having a plurality of curved openings at the

corners and intermediately adjacent to the box sides, a cue in the form of a spring gun operating a ball and having a thumb rest intermediate of its barrel portion and a ¹⁵ glancing block adjustable rotatably and having a flat ball surface and a semicircular ball surface for caroming the ball to the sides or board openings.

Signed at Montreal, Canada, this 9th day 20 of September, 1921.

HENRY THOMAS PYE.
